UNITED STATES PATENT OFFICE.

FREDERICK M. OPITZ, OF CHICAGO, ILLINOIS, ASSIGNOR, BY MESNE ASSIGNMENTS, TO
PERFEX RADIATOR COMPANY, OF RACINE, WISCONSIN, A CORPORATION OF WIS-
CONSIN.

RADIATOR.

1,134,274.

Specification of Letters Patent. Patented May 23, 1916.

Application filed January 30, 1911. Serial No. 605,390.

To all whom it may concern:

Be it known that I, FREDERICK M. OPITZ, a subject of the Emperor of Germany, residing at Chicago, in the county of Cook 5 and State of Illinois, have invented certain new and useful Improvements in Radiators, of which the following is a description.

My invention relates to means for cooling the circulating fluid employed to control the 10 temperature of gas engine cylinders or other parts in motor vehicles and the like.

The object of my invention is to provide a simple, strong and highly efficient device of the kind described, arranged to employ the 15 air as a medium for cooling the liquid in the radiator.

To this end my invention consists in the novel construction, arrangement and combination of parts herein shown and described, and more particularly pointed out in the claims.

In the accompanying drawings wherein like or similar reference characters indicate like or corresponding parts: Figure 1 is a 25 front elevation of my improved radiator. Fig. 2, is an enlarged fragmentary section of the same taken substantially on line 2—2 of Fig. 5. Fig. 3 is an enlarged fragmentary section taken substantially on line 3—3 of Fig. 5. Fig. 4 is an enlarged end view of a part of the cellular portion of my radiator. Fig. 5 is a section taken substantially on line 5—5 of Fig. 2. Fig. 6 is a section taken substantially on line 6—6 of Fig. 2. Fig. 7 35 is a perspective detail of the parts employed for forming a section of my radiator the same being in substantially their normal relation to each other but separated laterally to more clearly show their form and construction. Fig. 8 is a perspective view similar to Fig. 7 showing a slightly modified form of my device.

In the preferred construction shown my device consists of a suitable formed frame 45 or casing comprising an inclosing band 1, provided with an inwardly extending marginal flange 2, at each edge the width of the flanges 2 being slightly greater at the top and bottom of the frame, as at 3 and 4, respectively, so as to form a pair of chambers or receptacles between the flanges.

The radiating or heat dissipating portion 55 of my device consists of a plurality of conduits of suitable form extending between the chambers 3 and 4 and adapted to permit a

circulation of the water or other cooling fluid between the chambers. In the preferred construction shown each conduit is substantially rectangular in cross section and curved longitudinally to form a series of 60 semi-cylindrical arches. The adjacent conduits are arranged to coöperate to form a plurality of series of openings each extending from the front to the back of the radiator, each series comprising a vertical row of 65 cylindrical openings alternating with a similar row of angular openings. In the preferred construction each tube consists of a plate 7 and a strip 8. The plate 7 is of rectangular shape bent to form a series of 70 evenly spaced semi-cylindrical arches extending transversely thereof and with flanges 9 and 10 at its opposite edges. As shown the flanges extend at substantially right angles to the body portion of the 75 plate and the width of the flanges correspond to the desired thickness of the channels. The bases of the several arches are connected by a longitudinal portion 11, the width of which is approximately double the 80 desired thickness of the channel. The strip 8 is also rectangular and formed to snugly fit between the flanges 9 and 10 and is bent to accurately correspond to the lateral configuration of the plate 7 when uniformly 85 spaced therefrom. Suitable means are provided to gage the distance between the strip and plate. In the preferred construction a part 14 at each edge of the strip is offset slightly from the body portion and formed 90 to accurately fit against the side of the plate. The shoulder 15 between the body portion of the strip and offset part 14 forms substantially the edge of the conduit and accurately corresponds in width to the width 95 of the flanges 9 and 10 upon the plate 7. If desired also a slight depression 16 is formed intermediate the edges of the plate 8 the depth of the depression corresponding to the width of the shoulder 15 so that when 100 the plate and strip are in contact, the wall of the depressions 16 will engage the plate and thereby gaging the distance between the central portions of the plate and strip. When thus constructed the strip is positioned between the flanges 9 and 10 and held in contact with the plate and the edges are united by solder, cement or other suitable material preferably filling the off-set portion of the strip on both sides of the plate 105

110

adapted to form a strong and fluid tight closure between them.

In constructing my radiator a plurality of the conduits above described, are brought into coöperative relation with each other as shown in Figs. 2, 3, and 4 and the points of contact between the several conduits are permanently connected with solder or other suitable cement to firmly hold the several conduits in the desired relation to each other, each conduit is of sufficient width to snugly fit between the flanges 2 of the frame 1 and of sufficient length to extend across the opening between the parts 3 and 4. The conduits are each of sufficient length to extend into the space between the flanges so that when soldered in place a fluid tight closure will be formed comprising the several conduits and the spaces between the flanges 2 at 3 and 4 so that the entire structure will be fluid tight. When thus constructed it is obvious that the fluid in the radiator will circulate through the conduits and between the flanges 2 at the sides of the frame. Where however, it is desired to secure the greatest possible efficiency a pair of partitions 17 and 18 are provided at the upper and lower ends respectively of the side portion of the frame between the flanges 2 and extending from the wall 1 to the wall of the adjacent conduit. The partitions 17 and 18 are each soldered or otherwise securely fastened in position and arranged to prevent the cooling fluid from entering the space between the flanges 2 and the partitions. This portion of the frame serves as a convenient part for attaching the radiators to the frame of the vehicle thereby avoiding leaks incident to straining the radiator at its point of attachment to the vehicle.

In the form shown in Fig. 8 the plate, strip and frame are each formed substantially as hereinbefore described except that the offset portions of the strip are entirely omitted and the shoulders 15 are formed at the extreme edges of the strip and adapted to coöperate with the flanges 9 and 10 to hold the members in their proper lateral relation to each other when assembling the device as well as to suitably space the members from each other and provide a sufficiently strong joint between them.

Having thus described my improvement it is obvious that various immaterial modifications may be made in my device without departing from the spirit of my invention hence, I do not wish to be understood as limiting myself to the exact form and construction shown.

What I claim as new and desire to secure by Letters Patent is:

1. In a cellular radiator, a plurality of rectangular conduits each comprising a plate and a substantially flat laterally projecting flange formed at each edge of said plate, in

combination with a strip formed to snugly fit between said flanges, means upon said strip adapted to engage said plate at an angle to said flange to gage the distance between the strip and plate, and means for permanently securing the parts together. 70

2. In a cellular radiator, a plurality of rectangular conduits each comprising a plate and a laterally projecting flange formed at each edge of said plate, in combination with a strip formed to snugly fit between said flanges, a part at each edge of said strip being offset laterally and formed to accurately fit against said plate to gage the thickness of said channel, and a body of metal inclosing said offset portions and filling the space between said flange and the adjacent edge of said conduit. 75 80

3. In a cellular radiator, a plurality of conduits each comprising a plate and a laterally projecting substantially flat flange formed at each edge of said plate, in combination with a strip formed to snugly fit between said flanges, a part at each edge of said strip formed to accurately fit against said plate at an angle to said flange to gage the distance between said strip and plate and means for permanently sealing the joint between said plates and strips. 85 90

4. In a cellular radiator, a plurality of conduits each comprising a plate bent to form a series of semi-cylindrical transverse arches and a laterally projecting substantially flat flange formed at each edge of said plate, in combination with a strip formed to snugly fit between said flanges, a continuous offset portion at each edge of said strip adapted to engage said plate to gage the distance between said strip and plate, and means for permanently securing the parts together. 95 100 105

5. In a cellular radiator, a plurality of conduits each comprising a plate and a laterally projecting flange formed at each edge of said plate, in combination with a strip formed to snugly fit between said flange, the body portion of said strip being bent to accurately correspond to the lateral configuration of said plate when uniformly spaced therefrom, a continuous offset portion at each edge of said strip adapted to engage said plate to gage the distance between said strip and plate, and means for permanently sealing the marginal joints between said plates and strips. 110 115 120

6. In a cellular radiator, a plurality of rectangular conduits, each comprising a plate bent to form a series of semi-cylindrical transverse arches and a laterally projecting flange formed at each edge of said plate, in combination with a strip formed to snugly fit between said flanges and bent to accurately correspond to the lateral arches of said plate when uniformly spaced therefrom, a continuous offset portion at each 125 130

edge of said strip adapted to engage said plate to gage the distance between said strip and plate, and a body of metal filling the space between said flange and the adjacent 5 edge of said conduit.

7. In a cellular radiator, a plurality of substantially rectangular conduits each comprising a plate and a laterally projecting flange formed at each edge of said plate, in 10 combination with a strip formed to snugly fit between said flanges a portion at each edge of said strip being offset laterally,

means attaching one side of said offset portion directly to the side of said plate, and means filling the space between the opposite 15 side of said offset portion and said flange and rigidly attached to each.

In testimony whereof, I have hereunto signed my name in the presence of two subscribing witnesses.

FREDERICK M. OPITZ.
